CONCENTRIC TYPE ELECTRODE

William J. Scott, Rugby, England, assignor to General Electric Company, a corporation of New York

Application November 29, 1951, Serial No. 258,851

Claims priority, application Great Britain
December 12, 1950

10 Claims. (Cl. 315—58)

The present invention relates to an improved concentric type electrode and particularly to an improved electrode structure for use as a keep-alive electrode in a high frequency gaseous discharge device.

The present invention is particularly applicable to electric discharge apparatus embodying gaps cooperating with resonant openings or slots and adapted for use in microwave apparatus, where it is desired to alter the electrical characteristics of the gap by causing a discharge to take place across it. The gap then acts as a variable attenuator. Transmit-receive (T-R) and anti-transmit-receive (A. T. R.) devices are examples of such electronic discharge apparatus. A suitable filling for devices of this character includes a rare gas, such as argon, at a pressure of 8 to 12 millimeters of mercury at room temperature, together with water-vapor at a pressure up to 4½ millimeters of mercury.

In discharge devices of this type, it is generally desirable to maintain a discharge in the neighborhood of the main gap, defined by the two main electrodes, which is to be rendered conducting by a discharge under predetermined conditions, such as high frequency voltage conditions across the gap. This is often accomplished by means of a keep-alive or ignition electrode which is disposed in such relation to one main electrode so that a constant potential connected between the keep-alive electrode and the main electrode maintains a glow discharge therebetween. Thus, a main discharge across the main gap occurs substantially instantaneously when the predetermined condition exists.

In one well-known construction, the keep-alive electrode is positioned concentrically within a hollow main electrode, a negative potential of the order of 1000 volts being connected through a resistance of several megohms between the hollow main electrode and the keep-alive electrode. The surrounding main electrode is of relatively small dimensions to give the desired capacity in cooperation with the opposed closely-spaced main electrode, and the concentric electrode is terminated short of this opening in order to confine the ionization to the region near the end of that one main electrode to a desired extent. Such a prior art arrangement with 1000 volts applied between the keep-alive electrode and the main electrode gives some tens or hundreds of microamperes in the glow discharge between the keep-alive and main electrodes, and maintains the number of free electrons in the radio frequency gap between the ends of the hollow main electrode and the opposing main electrode, which may be either solid or hollow.

It has been found difficult in quantity production to make and position the keep-alive electrode with sufficient accuracy and with adequate clearances to the surrounding electrode to give economic assembly and reasonably long operating life. It is necessary that keep-alive electrode be positioned at a greater distance from the opposing main electrode than from the surrounding main electrode in order to prevent the keep-alive discharge from injecting an excessive number of electrons between the

2

main electrodes and, in this way, cause unwanted signal attenuation. To provide satisfactory operation of the prior art keep-alive structures of the type described, it has been necessary to keep the structure small and mount the keep-alive electrode within and in closely spaced relation to the end of the surrounding hollow electrode.

It has been found that during a discharge, transfer of metal, for example by sputtering, from the keep-alive electrode end onto the ends of the main electrode has occurred. This may result in shorting of the keep-alive electrode and one of the main electrodes, or in some cases, shorting of the main electrodes. Also, as a result of this sputtering, the gap capacity, as measured between the main electrodes, and accordingly the tuning of the gap circuit, tends to vary.

The present invention relates to hollow electrodes of the kind adapted to cooperate with an opposing electrode to form a gap in microwave discharge devices, and particularly to such an electrode including a concentric keep-alive electrode.

According to the present invention, the outer hollow electrode of the general type described above is provided with an electrode tip adapted to define with the opposing electrode the discharge gap and extending closer to the gap than the centrally disposed keep-alive electrode, thus permitting the keep-alive electrode to extend longitudinally beyond the body portion of the hollow electrode. This construction allows the use of a larger body portion of the hollow electrode and easier positioning of the keep-alive electrode beyond the end thereof, and at the same time, the gap spacing and the capacity of the gap is determined by the position and dimensions of the electrode tip. The electrode tip is preferably in the form of a relatively open structure having a transverse portion which cooperates with the opposing main electrode since this gives the relatively small area in opposed relation to the other main electrode and leaves an open structure which facilitates the positioning of the keep-alive electrode during manufacture.

The electrode tip, and particularly the transverse section, also act as a shield to protect the narrow gap between the tip and the opposed main electrode from any metal sputtered from the keep-alive electrode. Additional features and advantages of my invention will become more apparent as the following description proceeds, reference being had to the accompanying drawing, and its scope will be pointed out in the appended claims. In the drawing, Fig. 1 is an elevational view in section of a discharge device having a keep-alive electrode assembly embodying my invention; Fig. 2 is a sectional view along the line 2—2 of Fig. 1; Fig. 3 is an elevational view, partially in section, showing both opposed electrode structures of similar construction; and Figs. 4—10 inclusive illustrate modifications of electrode structures embodying my invention.

Referring now to Fig. 1 of the drawing, I have shown my invention embodied in a discharge device including a short section of rectangular wave guide defined by a metallic wall 1, having at the ends thereof, coupling flanges 2 and 3 for coupling at one end with a wave guide extending between a transmitter and an antenna, for example, and at the other end for connection with the receiver. This wave guide section is closed at the ends by window assemblies each including a metallic frame 4 and a dielectric window 5. The windows may to advantage be formed of glass and are suitably dimensioned with respect to the frequency of operation of the system in which the device is to be used.

Extending across the wave guide section 1 intermediate the ends thereof are transverse metal partitions 6 and 7 which are spaced apart, and from the ends of the device in the direction of propagation of waves through

the device, a distance corresponding to one-quarter wavelength at the operating frequency. The partitions, as shown in Fig. 2, are each provided with a rectangular opening or slot 8 which is centrally located with respect to the cross section of the device. A pair of conical members 10 and 11 are supported from the opposite side walls of the wave guide in line with partition 7. These conical members provide a narrow gap 12 at the plane of the partition. A similar conical member 13 extends upwardly from the lower wall of the guide at the plane of partition 6, and a keep-alive electrode assembly 14 is mounted in the upper wall of the guide and terminates in opposed relation to the conical electrode 13.

The electrode assembly 14 includes a generally cylindrical outer electrode 15 hermetically joined to the wall of the guide by means of a suitable flange member 16 which may be brazed to both the guide and the electrode member 15. A keep-alive electrode 17 in the form of an elongated conductor is supported in concentric and insulated relation with respect to the outer electrode 15 by means of a glass sealing member 18. The lower end of the keep-alive electrode extends below the lower end of the outer electrode 15, and is covered, except at the tip portion or transverse end surface, with a glass or other insulating coating 19. A tip portion for the outer electrode is provided by a strap member 20 which, in the particular form illustrated, is in the form of a U-shaped wire loop having the ends of the U brazed or welded to the outer conductor 15, and the base of the U portion, extending in a generally parallel and closely spaced relation with respect to the opposing electrode 13. As illustrated, the opposing main electrode 13 may be tapered to provide a narrow surface in proximity to the wire member 20, and preferably extending at right angles thereto. In this manner, it is possible to obtain relatively small effective gap area with relatively rugged electrode construction. It will be appreciated that the electrodes 10 and 11 may be provided with narrow portions extending at right angles with respect to one another, if desired, in order to provide gap capacity which is similar to that of the electrodes 13 and 14.

The end of the keep-alive electrode 17 is spaced from the tip 20 by an amount which is termed the "retraction." The retraction is fairly critical and varies with the gas filling, composition and with the electrode dimensions. As was pointed out earlier in the specification, it is desired to obtain a certain amount of ionization in the vicinity of the gap between the main electrodes without having an undesirable amount of ionization between the main electrodes under those conditions when it is desired that the gap be non-conducting. In one particular device embodying the present invention, the main electrodes and keep-alive electrodes were of iron or a ferrous alloy and the wire 20 was of .020" diameter nickel wire. All the metal parts exposed to the interior of the device were electroplated with silver or copper. The retraction exceeded .020".

In Fig. 3, I have shown a modification of my invention in which both electrodes are of similar construction. As illustrated, each electrode assembly includes an outer main electrode sleeve 21 and an inner make-alive electrode 22, coated with glass or a similar insulating material 23. A U-shaped wire loop 24 is secured to the outer electrode in the same manner as the loop 20 shown in Fig. 1. As illustrated, the two electrode assemblies are mounted in opposed relation and rotated 90° with respect to each other so that the bases of the U-shaped loops 24 are mutually perpendicular providing a small area gap. As illustrated, the gap 25 between the spaced portions of the loops 24 is slightly less than the retraction 26, between the inner surface of the loops and the ends of the keep-alive electrodes 22.

In Figs. 4 and 5, I have shown a modified form of the exterior or main electrode in the form of a cylinder 27 having an integral strap 28 forming the electrode tip.

and corresponding generally to the wire loop 24. Figs. 6-10 illustrate modified forms of the tip construction which may be used in accordance with my invention. The parts of the electrode structure in general correspond to those of Fig. 3 and corresponding parts and have been designated by the same reference numerals. In Fig. 6 two U-shaped members 24 have been employed. This construction gives better radio frequency shielding of the tip of the keep-alive electrode. In Fig. 7, a similar construction is used except that the loop 24 is positioned the same as in connection with Fig. 3 and additional wire posts 29 are employed to give the additional shielding. In Fig. 8, the electrode tip is formed by a generally U-shaped wire mesh 30 which is employed in place of the wire loop 24. In Figs. 9 and 10, the tip portion is provided by a plurality of transversely extending wires 31 which are bonded to longitudinally extending portions 32 formed integrally with the outer electrode 21.

While the wires illustrated have been of circular cross section, wires or straps of non-circular cross section may be used and local sharp portions or edges may be employed to increase the radio frequency field strength of particular parts of the gap between the electrode tips, if desired.

While I have shown and described particular embodiments of my invention, it will be apparent to those skilled in the art that changes and modifications may be made without departing from my invention in its better aspect and aim therefore in the appended claims to cover all such changes and modifications as fall within the true spirit and scope of my invention.

What I claim as new and desire to secure by Letters Patent of the United States is:

1. A high frequency electric discharge device comprising a main electrode and a concentric-type electrode structure mounted in endwise spaced and opposed relation with respect thereto to define a discharge gap, said concentric-type electrode structure comprising an outer member having a longitudinal passage therethrough, a keep-alive electrode supported within said passage in insulated relation to said outer member and having the end thereof extending beyond the end of said outer member toward said main electrode, said outer member including a member small in cross section in comparison with said outer member extending from the outer surface of said outer member longitudinally beyond said keep-alive electrode and having a portion spaced from the end of said main electrode forming said discharge gap.

2. A high frequency electric discharge device comprising a main electrode and a concentric electrode structure mounted in opposed endwise and spaced relation with respect thereto, said concentric electrode structure comprising an outer conducting member having a longitudinal passage extending therethrough, a keep-alive electrode supported in said passage in insulated relation with respect to said conducting member and extending longitudinally beyond the end of said conducting member and a generally U-shaped conductor joined to the outer surfaces of the side walls of said conducting member with the base of the U-shaped conductor extending transversely across the passage in said conducting member and cooperating with the end of said main electrode forming said discharge gap.

3. A high frequency electric discharge device including a main electrode and a concentric-type electrode supported in opposed endwise and spaced relation with respect thereto to provide a discharge gap, said concentric-type electrode comprising an outer conducting member having a longitudinal passage extending therethrough, a keep-alive electrode including a portion supported in said passage in concentric relation with respect to said conducting member and extending longitudinally beyond the end of said conducting member, said portion of said keep-alive electrode including a transverse end surface and being completely coated with an insulating material except for

said transverse end surface, and a conductive element of small cross section in comparison with said conducting member extending longitudinally from the side wall of said conducting member toward said main electrode and cooperating with said oppositely mounted main electrode forming said discharge gap.

4. The device as defined in claim 3 wherein said conductive element is U-shaped and is integral with said conducting member.

5. An electrode structure for use in a high frequency electric discharge device comprising an outer conducting member having a longitudinal passage extending therethrough, a keep-alive electrode supported in said passage in insulated relation with respect to said conducting member and extending longitudinally beyond the end of said member and a generally U-shaped conductor joined to the side walls of said conducting member with the base of the U-shaped member extending transversely across the passage in said conducting member, a second electrode oppositely mounted with respect to said electrode structure and having an elongated transverse surface extending substantially perpendicular to the transverse portion of said U-shaped member and forming therewith a gap.

6. An electrode structure for use in a high frequency electric discharge device comprising an outer conducting member having a longitudinal passage extending therethrough, a keep-alive electrode including a transverse end surface and being supported in said passage in said conducting member with said transverse end surface extending longitudinally beyond the end of said member, said keep-alive electrode being completely coated with an insulating material except for said transverse end surface, a generally U-shaped conductive structure including a plurality of conductors joined to the side walls of said conducting member with the base of the U-shaped structure comprising a plurality of individual conductive elements extending transversely across the passage in said conducting member, and a second electrode oppositely mounted with respect to said U-shaped structure for cooperation with said plurality of individual conductive elements and forming a discharge gap therewith.

7. An electrode structure for use in a high frequency discharge device, comprising an outer conducting member having a longitudinal passage extending therethrough, a keep-alive electrode supported in said passage in insulated relation with respect to said conducting member, a generally U-shaped conductor joined to the side walls of said conducting member with the base of the U-shaped conductor extending transversely across the passage in said conducting member, and a second electrode oppositely mounted with respect to said electrode structure and having a generally U-shaped conductor disposed substan-

tially perpendicular to the transverse portion of said U-shaped conductor and forming therewith a gap.

8. An electrode structure for use in a high frequency discharge device, comprising an outer conducting member having a longitudinal passage extending therethrough, a keep-alive electrode insulatedly supported in said passage, a pair of generally U-shaped conductors projecting from the side walls of said conducting member with the bases of the U-shaped member extending in substantially mutual parallel relation and in diametrically opposed relation across the passage in said conducting member, and a second electrode oppositely mounted with respect to said conducting member and having an elongated transverse surface spaced from said U-shaped conductors and forming therewith a gap.

9. An electrode structure for use in a high frequency discharge device, comprising an outer conducting member having a longitudinal passage extending therethrough, a keep-alive electrode supported in said passage in insulated relation with respect to said conducting member, a generally U-shaped wire mesh joined to the side walls of said conducting member with the base of the mesh extending transversely across the passage in said conducting member, and a second electrode oppositely mounted with respect to said conducting member and forming with said mesh a gap.

10. An electrode structure for use in a high frequency discharge device, comprising an outer conducting member having a longitudinal passage extending therethrough, an auxiliary electrode insulatedly supported in said passage, a generally U-shaped conductor joined to the side walls of said conducting member with the base of the U-shaped conductor extending transversely across the passage in said conducting member, a pair of conductive rod members joined to the side walls of said conducting member and arranged in space quadrature with respect to said U-shaped conductor, and a second electrode oppositely mounted with respect to said electrode member and having an elongated transverse surface extending substantially perpendicular to the transverse portion of said U-shaped conductor and forming therewith a gap.
